UNITED STATES PATENT OFFICE

148,455

DESIGN FOR A STENOGRAPHER'S NOTEBOOK STAND OR SIMILAR ARTICLE

Michael Bleich and William B. Axelrod,
New York, N. Y.

Application March 21, 1947, Serial No. 137,800

Term of patent 7 years

(Cl. D74—1)

To all whom it may concern:

Be it known that we, Michael Bleich and William B. Axelrod, citizens of United States, residing at New York city, in the county of Kings and State of New York, have invented a new, original, and ornamental Design for Stenographer's Notebook Stand or Similar Article, of which the following is a specification, reference being had to the accompanying drawing, forming part thereof.

In the drawing:

Fig. 1 is a top view of a stenographer's notebook stand embodying the invention.

Fig. 2 is a side elevational view thereof.

Fig. 3 is an end elevational view thereof.

Fig. 4 is a cross-sectional view taken on line 4—4 of Fig. 2.

We claim:

The ornamental design for a stenographer's notebook stand or similar article, as shown.

MICHAEL BLEICH.
WILLIAM B. AXELROD.
